UNITED STATES PATENT OFFICE.

WILLIAM L. MILES, OF SAGINAW, MICHIGAN.

TRACK-HANDLING DEVICE FOR DREDGES.

1,196,012.

Specification of Letters Patent. Patented Aug. 29, 1916.

Application filed October 19, 1915. Serial No. 56,708.

To all whom it may concern:

Be it known that I, WILLIAM L. MILES, a citizen of the United States, residing at Saginaw, in the county of Saginaw and State of Michigan, have invented certain new and useful Improvements in Track-Handling Devices for Dredges; and I do hereby declare the following to be a full, clear, and exact description of the invention, such as will enable others skilled in the art to which it appertains to make and use the same.

This invention relates to dredges and excavating machines and pertains more particularly to dredges mounted to travel on temporary tracks, the tracks being removed from behind the machine and relaid ahead of the machine as the work of excavating progresses.

The invention relates still more particularly to an improved means for conveniently and quickly taking the track sections from the rear of the machine, transporting them to the front and relaying them in advance of the machine.

A further object of the invention is to provide a simple and inexpensive device for transporting the track sections, as above noted, the device comprising longitudinally disposed beams or rails, which carry the transporting carriage, the beams themselves being adapted to serve as tie members or stiffeners for the frame of the dredge truck.

With these and certain other objects in view, which will appear later in the specification, my improvement consists in the devices described and claimed, and the equivalents thereof.

In the drawings, Figure 1 is a side elevation of a dredge with my improvement attached. Fig. 2 is a top plan view. Fig. 3 is a top plan view of one form of truck. Fig. 4 is a transverse section, to reduced scale, taken on line 4-4 of Fig. 3. Fig. 5 is a part sectional elevation of a modified form of truck and track.

As is clearly shown in the drawings, 1 represents the track, on which the dredge is mounted.

2 is the frame of the dredge truck, and 3, 3 are longitudinal beams extending parallel with the track 1 and mounted on the frame 2. The forward end 4 of each beam 3 projects ahead of the front wheels 5 of the

dredge, and the rear end 6 projects to the rear of the back wheels 7.

Upon each beam 3, 3 a carriage 8 is mounted, upon which the rails 1 may be transported from the rear to the front of the dredge. The preferable manner in which the carriage 8 is mounted upon the beams 3, 3 is shown in Fig. 4, where 9, 9 are flanged wheels riding upon the lower inner flanges of the beams 3, 3, the wheels being inclined to suit the inclination of the flanges. The wheels are mounted upon a suitable iron frame 10, which carries a block 11, or its equivalent, surmounted by a suitable table 12. This arrangement enables the table 12 to be kept close down to the top of the I-beam track 3 and the I-beams protect the wheels 9.

A modified form of table and track is shown in Fig. 5, where wheels 9 are mounted on opposite sides of a single I-beam track 13, the table 14 being carried by an inverted U-frame 15 mounted upon the wheels 9. To prevent sidewise tilting of the table, suitable guide-rollers 16 are mounted on the frame 15, adapted to engage the sides of the upper flange of the I-beam 13.

The tracks 3, or the track 13, may be bolted, or otherwise, rigidly secured to the frame 2 of the truck, thereby stiffening the frame and imparting rigidity to the dredge. The tracks are adapted to be easily applied to any ordinary form of dredge frame, constituting, together with the carriage, an effective device for transporting rails or other material from one end to the other of the dredge while the dredge is in operation.

Having thus described my invention, what I claim and desire to secure by Letters Patent is:

1. The combination of a dredge frame, a horizontal flanged track secured to the dredge frame and having its front and rear ends projected respectively in advance of and to the rear of the dredge frame, and a movable carriage mounted thereon, said carriage comprising wheels adapted to roll upon the lower flange of said track, a frame carried by said wheels and a table on said frame, said table disposed above the upper flange of said track.

2. The combination of a dredge frame, a horizontal track secured to the dredge frame and having its front and rear ends pro-

jected respectively in advance of and to the rear of the dredge frame, said horizontal track comprising a flanged beam, and a movable carriage mounted thereon, said carriage comprising inclined wheels adapted to roll upon the lower flanges of said track, a frame mounted on said wheels, and a table on said frame, said table disposed above and

in proximity to the upper flange of said beam, for the purposes set forth. 10

In testimony whereof, I affix my signature in presence of two witnesses.

WILLIAM L. MILES.

Witnesses:

NELLIE M. ANGUS,
ROY WALLIS.
